COLLAPSIBLE BABY CARRIAGE

Angus Christopher Firth and Frederick John Sheldon,
Shipley, England, assignors to Lawrence Wilson & Son
Limited, Leeds, England

Filed Mar. 4, 1974, Ser. No. 447,569

Claims priority, application Great Britain Dec. 19, 1973

Term of patent 14 years

Int. Cl. D12—12

U.S. Cl. D12—129

FIG.1

FIG.2

FIG.3

FIG. 1 is a front elevational view of a collapsible baby carriage showing our new design;

FIG. 2 is a side elevational view thereof, the opposite side being a mirror image of the side shown;

FIG. 3 is a bottom plan view thereof;

FIG. 4 is a rear elevational view thereof;

FIG. 5 is a front perspective view thereof;

FIG. 6 is a perspective view showing the collapsible baby carriage in its collapsed state.

We claim:

The ornamental design for a collapsible baby carriage, as shown.
